UNITED STATES PATENT OFFICE.

CHRISTIAN GIRL AND WAYNE E. DUNSTON, OF DETROIT, MICHIGAN, ASSIGNEES TO
THE C. G. SPRING COMPANY, OF DETROIT, MICHIGAN, A CORPORATION OF DELA-WARE.

DESIGN FOR AN AUTOMOBILE BUMPER.

Application filed December 15, 1923. Serial No. 8,041. Term of patent 14 years.

To all whom it may concern:

Be it known that we, CHRISTIAN GIRL and WAYNE E. DUNSTON, citizens of the United States, residing at Detroit, in the county of Wayne and State of Michigan, have invented a new, original, and ornamental Design for Automobile Bumpers, of which the following is a specification, reference being had to the accompanying drawing, forming part thereof, wherein—

Fig. 1 represents a plan view and Fig. 2 an elevation of a bumper exhibiting our new design.

We claim:

The ornamental design for an automobile bumper, as shown.

CHRISTIAN GIRL.
WAYNE E. DUNSTON.
